UNITED STATES PATENT OFFICE.

WILLIAM C. WOOD, OF WASHINGTON, DISTRICT OF COLUMBIA, ASSIGNOR
TO THE EICKEMEYER FELTING COMPANY, OF NEW YORK, N. Y.

FULLING-MILL.

SPECIFICATION forming part of Letters Patent No. 249,440, dated November 8, 1881.

Application filed August 24, 1881. (No model.)

To all whom it may concern:

Be it known that I, WILLIAM C. WOOD, of the city of Washington and District of Columbia, have invented certain new and useful Improvements in Fulling-Mills; and I do hereby declare that the following specification, taken in connection with the drawings furnished and forming a part of the same, is a clear, true, and completed description of the several features 10 of my invention.

A mill embodying my improvements is applicable to general service in fulling or felting fabrics of various kinds; but I have devised the same with special reference to felting or fulling hat-bodies and other goods of a similarly delicate nature.

Fulling-mills as heretofore organized for the purposes suggested may be fairly divided into three general classes, as follows: beater-mills, 20 having hammers which beat upon the goods; roller-mills, having rollers between which the goods in mass are passed and repassed; and cylinder-mills, involving skeletonized rolls or endless belts, constituting a fulling-bed, within 25 which the goods are merely tumbled in mass. Mills belonging to each of these classes have been variously constructed and arranged, but without materially changing their general mode of operation so far as my knowledge extends. Mills of each of these classes possess 30 certain desirable capacities when viewed with reference to particular results, but they are accompanied in each case with certain disadvantages when considered with reference to 35 obtaining certain other desirable results.

Broadly stated, the prime object of my improvements is to combine in one mill such a combination of elements as will enable it to operate in felting or fulling delicate goods with 40 all or many of the desirable peculiarities of operations incident to mills belonging to each of the classes referred to, and at the same time to obviate many of their well-known disadvantages, among which may be stated the liability 45 of injury to delicate goods by cutting, unduly abrading, and straining, as in an ordinary beater-mill, the labor and expense of attendants in handling the goods incident to their repeated passage through the roller-mills, and 50 the tardiness in operation common to the cylinder-mill.

I recognize the fact that mills operating upon the beater principle have recently been so constructed and organized as to operate with but little if any liability to injury to the delicate goods—as, for instance, in that class of Eickemeyer mills in which falling beaters are well controlled and capable of being graduated for delivering light or heavy blows, and also in a certain other class of Eickemeyer mills which 55 embody fulling-beds composed of beaters.

I have provided in my mills for an abundant circulation of well-heated water or fulling-liquid within the bed, and also for the application of live steam to the contents of a bed in a manner highly favorable to good results in fulling or felting, and the apparatus devised by me for this purpose is applicable to fulling-mills 60 of any class.

After describing in detail several mills embodying more or less of my improvements, the features deemed novel will be designated in the several claims hereunto annexed.

Referring to the four sheets of drawings, Figure 1, Sheet 1, is a central longitudinal vertical section of a mill embodying the principal features of my invention. Fig. 2, Sheet 1, is a transverse vertical section of the same. Fig. 3, Sheet 1, is a horizontal section of a portion of a mill-tank and my apparatus for circulating water and steam. Fig. 4, Sheet 2, is a longitudinal vertical section of a mill of somewhat different construction, but embodying certain features of my invention. Fig. 5, Sheet 2, is an end view of the same, with the adjacent end 70 of the tank removed. Fig. 6, Sheet 3, is a lateral vertical section thereof on line y, Fig. 4. Fig. 7, Sheet 3, is a central longitudinal vertical section of another form of mill embodying certain features of my invention. Figs. 8 and 9, Sheet 3, are detail views, illustrating the construction of the cylinder-heads and bars suitable for the machine, Fig. 7. Fig. 10, Sheet 4, is a central longitudinal vertical section of a mill similar to Fig. 1, but having a double 75 bed and beaters of a different character. Fig. 11, Sheet 4, is a lateral vertical section of Fig. 10 on line x. Fig. 12, Sheet 4, is a sectional view of the striking end of a beater.

I will first describe the machine shown at 100 Figs. 1, 2, and 3.

The tank A may be of any suitable form and

size and of such depth as will enable the goods to be submerged, or nearly so, if desired, and also with sufficient capacity to hold an ample supply of water or suitable fulling-liquid beneath the bed, for maintaining a continuous circulation, as hereinafter described, whenever an actual submerging of the goods is undesirable.

The fulling-bed B is composed of somewhat flexible wooden or metallic bars *a*, secured to endless belts *b* or chains, as in prior well-known English machines. In this instance the belts *b* are preferably composed of rubber and canvas and embodying longitudinal strands of wire, which will render them practically non-extensible, and to these belts the bars *a* are so riveted as to bring them next to the surface of the driving-cylinder *c*, and in contact at each side with the largest periphery of the bed-drum *d*, said drum revolving with the endless bed. The bed-drum *d* is rotatively mounted upon a loose or fixed trunnion or axis, *e*, which is tubular and perforated. The bed-drum is smaller in the center than at either end, as shown, so as to afford a space between it and the endless bed, which is deepest at the center of the bed. The drum is also radially perforated, as at *d'*, the perforations registering, as the drum revolves, with corresponding perforations in the hollow trunnion *e* for the introduction of steam or hot water, as hereinafter explained. The flanges or ends of the bed-drum are clad with an elastic cushion, *d''*, after the manner of a wheel-tire, and the bars *a* are seated thereon. If desired, guides may be employed for maintaining the bars in close contact with the peripheries of the flanges adjacent to the line at which the beaters operate.

Suspended from a suitable rock-shaft are two beaters, C, which are forcibly vibrated by a set of tappet-arms, *f*, on a suitably-driven shaft in a manner well understood. As the blows are given while the fulling-bed is in motion, I provide for the beaters a roller-toe, *g*, the periphery of which is also preferably cushioned, as seen in Fig. 12, so that it may strike with spring-like action against the bars, which responding to the blow, being themselves flexible and springy, and also seated on the cushioned flanges of the bed-drum, communicate a percussive blow against the contents of the mill, which are supported on said bed.

As thus far described, it will be readily obvious that while the mill is in action the contents of the bed will be raised and tumbled backwardly by the bed, and will be also caused to tumble toward the center of the bed because of the concavity of the bed-drum, and be gradually squeezed during their downward and released during their upward passage, and that just prior to their release (or just after, according to the direction in which the bed is rotated) they will be beaten without abrasive action from the beaters.

The construction and arrangement of the bed, the bed-drum, and the beaters may be widely varied without departure from my in-

vention, and in some cases the bed-drum may be dispensed with, as will be hereinafter indicated.

It being essential for good results that an abundance of hot water, and sometimes steam alone, be employed in felting and fulling operations, I have devised a certain novel system of circulation and distribution which is embodied in the machine so far described. For the first time I have, as I believe, applied to fulling-mills the principles involved in the steam siphon-pump, and I am not aware that they have ever before been applied in any connection as a means for effectively heating water and the circulation thereof.

I rely upon a steam-nozzle for usefully delivering live steam, when desired, alternating at will with a continuous circulation of water, meantime heating it in transit. The details of this portion of the apparatus are shown in Fig. 3. The steam-nozzle *h* enters the pipe *h'* within the tank near the bottom and at one end thereof, and said pipe is provided with a series of openings, *h''*, in such relation to the nozzle that the water in which said pipe is submerged is drawn inward and forced through the pipe *h'* to the vertical pipe *h'''* outside the tank; thence to the original spray-pipe *h''''*, which overlies the fulling-bed. The spray-pipe *h''''* is perforated on its lower side, the apertures being increased in size as their location approaches the outer end of the pipe to secure a reasonably uniform downward discharge of water upon the contents of the bed. A cock at *h''''* enables the discharge of water to be graduated at will. For cutting off the water and the delivery of steam alone the nozzle may obviously be so arranged as to be advanced; but I prefer a simple rotative register or sleeve valve, *h'''''*, which surrounds the pipe *h'* at the openings *h''*, and is also provided with corresponding openings, and with a worm-gear which is engaged by the vertical worm-shaft *h''''''*, readily accessible for rotating the sleeve and cutting off the water-supply.

As the steam would do but little good if projected downward from pipe *h''''*, I have employed the hollow perforated trunnion *e* by connecting it at its outer end with the vertical pipe *h'''*, so that when the cock *h''''* and the sleeve-valve *h'''''* are closed, live steam may be delivered through the radial ducts *d'* directly among the hats or other articles within the bed. With this arrangement or system of heating and wetting an extremely wide range of service may be performed. The tank may be well filled with water, and the nozzle-injector employed for heating and circulating purposes only; or the water in the tank need only well cover pipe *h'*, and be made to continuously flow through and over the contents of the bed, and when the tank is thus charged or empty the water may be dispensed with and only live steam applied. For properly guarding the sleeve valve and nozzle from the receipt of fiber and other obstructive matter it is housed within a large wire-gauze casing, *h''''''*. This system of heating water and circulating the same is of more or

less value in all fulling-mills, regardless of their construction or general mode of operation, and I do not therefore limit this portion of my invention to this particular type of fulling-mill.

5 I do not limit myself to the precise construction and arrangement of the nozzle and the adjacent parts which I have shown and described, so long as the jet of steam be capable of inducing a vacuum at the rear thereof for drawing in the liquid and then forcing the same through the circulating pipes, and the parts be also so arranged that either steam or hot water may be delivered upon or through the contents of the fulling-bed. Should it ever be 10 deemed desirable, the heating capacity of the nozzle may be supplemented by a steam-coil in the bottom of the tank.

The mill shown in Figs. 4, 5, and 6 is similar to that previously described, but differs therefrom mainly in having no bed-drum between which and the bed the goods are passed. The endless bed in this instance is composed of endless belts b' , one near each side, and to their outer surfaces the bars a' are riveted, so that 15 the belts lie between them and the disks i , which, like the corresponding surfaces of the bed-drum, are preferably clad with cushions, as before described. Beaters, substantially like those before described, are here employed, 20 of which there may be one or more, according to the width of the bed. The circulation of hot water is effected in this mill as in Fig. 1; and, if desired, one or both of the trunnions of disks i may be tubular and connected with the 25 vertical outside pipe and employed with good results for distributing water or steam, as in the other mill. In operation this mill will be somewhat less rapid in fulling than the one previously described.

30 The mill shown in Figs. 7 and 8 is of the cylindrical type. The tank, water heating and circulating apparatus, and beaters are substantially as heretofore described, except that the latter are arranged to deliver their blows 35 against a lower portion of the bed, so that they will strike upwardly. The bars a^2 may be variously mounted; but I prefer that the cylinder-heads be cushioned peripherally, and the bars secured by bolts which pass loosely 40 through them, and snugly through the cushion into the heads, as clearly indicated in Fig. 9. The cylinder-heads may, however, be radially recessed from the periphery and the bars partially located in the recesses, secured 45 by bolts, as heretofore, and cushioned against the blows of the beater by brass spiral springs which surround the bolts and are seated upon the inner ends of the recesses. In this mill the cylinder-heads have tubular trunnions, 50 which are capped inside the cylinder with a perforated cup-shaped plate, k , which serves as a rose-jet for the delivery of either hot water or steam upon and among the contents of the bed.

55 The mill shown in Figs. 10 and 11 has the same system of steam and water distribution before described in connection with Fig. 1.

This bed-drum has, however, a central flange, virtually dividing the fulling-bed into two compartments, and overhanging this flange or rim 70 is a pendent partition, l , which prevents the goods from being caught between said flange and the bed while tumbling from one side to the other. The endless bed m is unlike any of those previously described, and although it 75 may embody the flexibly-cushioned bars, I prefer for this mill, or any one having a very narrow bed, an endless bed composed of a many-ply fabric of cotton or linen—such, for instance, as is woven on the well-known "Baker" loom, 80 and with occasional strands of interwoven straight wire warp, (copper or tinned iron or steel,) and also re-enforced opposite the center of each bed, as at m' , with a suitable band for receiving the blows of the beaters, of which 85 one or two may be employed for each bed or compartment thereof. In this mill I have organized beaters which operate on the spring-ran principle, with obvious and well-known means for adjusting either the power of the 90 springs or the length of the stroke; and the beaters previously described may also be provided with mechanism for graduating the force of the blows applied thereby, after the manner heretofore employed in the certain beater-mills 95 containing the ordinary bed. In this mill the endless bed not being composed in part of bars cannot so readily free itself of liquids discharged therein, and therefore I provide the end flanges of the bed-drum with numerous 100 lateral apertures, n , through which liquid freely passes back into the tank. In its operation the rolls on the ends of the rams may be arranged to press firmly inwardly when not in the act of striking, thus compressing the central portion of the contents of the bed and contributing to the fulling operation. With a bed 105 of this character elastic rod beaters may be employed to strike the bed lengthwise of the beaters; but in such case they should be downwardly bent or curved and arranged to strike against the bed with their curved surfaces, in order to operate smoothly and without undue abrasion of the beater-surface of the bed.

In the construction of my mills I contemplate the employment of such materials as may prove best suitable, having due reference to economy and durability, and the same is true of mechanical details in construction and arrangement of the several parts; and while I prefer 115 a mill embodying all of the several features of my invention, portions thereof may be separately employed to advantage in other mills, as hereinbefore indicated.

When large tanks are not required suitable 125 receptacles may be employed whereby a continuous circulation of liquid may be afforded; or, if this latter feature be not desired, and steam only employed, dripping vats or conduits need only be provided.

With some classes of work fair results may be obtained with the machine Fig. 7, if the bed be turned to and fro on its trunnions, instead of continuously rotated, provided the motion

be sufficient to cause the contents to effectually change their position in the bed.

I am well aware that it is not new to employ, in connection with a beater or beaters and a fulling-bed, one or more continuously-moving endless aprons for containing articles to be felted; but as heretofore employed said aprons extended with their lower ends into the fulling-bed between the beaters and beater-heads, 10 as shown, for instance, in the United States Letters Patent of Hopkins, July 22, 1856, No. 15,375.

Having thus described my invention, I claim as new and desire to secure by Letters Patent—

- 15 1. The combination, substantially as hereinbefore described, of a flexible or yielding fulling-bed, beaters which deliver blows against the outer surface of the bed, and a bed-drum within the bed, between which and the inner 20 surface of said bed articles to be fulled or felted are alternately compressed and released from pressure, as set forth.
2. The combination, substantially as hereinbefore described, of a rotating flexible fulling-bed, beaters which strike against the outside 25 of the bed, and a drum within the bed.
3. The combination, substantially as hereinbefore described, of an endless moving flexible fulling-bed and beaters which deliver blows 30 against the outer surface of said bed, and there-

by communicate shocks or blows to its contents, as set forth.

4. The combination, with a continuously-movable fulling-bed which contains and loosely tumbles the goods to be felted, of a tank containing the whole or a portion of said bed, and means for continuously circulating water or other fulling-liquid from the tank through the bed and its contents, substantially as described. 35

5. The combination, with a fulling-mill bed, 40 of a water-receptacle, a steam-injector, and suitable pipes and cocks, substantially as described, whereby said nozzle may be relied upon for continuously circulating water from the tank through the bed and upon its contents, or for the delivery of steam alone, substantially as set forth. 45

6. The combination, substantially as described, with an endless rotating fulling-bed, which contains and loosely tumbles goods to be felted or fulled, of means, substantially as described, for delivering steam in jets within the bed and centrally among the contents thereof as they are tumbled by the movement of said bed. 50

WM. C. WOOD.
